Int. Cl. D21—01
U.S. Cl. D34—15

FIG. 1 is a top view of an optical illusion puzzle showing our new design;

FIG. 2 is a front elevational view thereof;

FIG. 3 is a bottom view thereof;

FIG. 4 is a side elevational view taken from the right of FIG. 1; and

FIG. 5 is an enlarged cross-sectional view taken substantially along the line 5—5 of FIG. 1.

The opposite side of FIG. 4 is substantially the same except the guide indentation at the upper edge is of a smaller length than that illustrated in FIG. 4.

The rear of the opposite side of FIG. 2 is substantially the same as FIG. 4 except that no guide indentation is present on the upper edge.

We claim:

The ornamental design for an optical illusion puzzle, substantially as shown and described.
